UNITED STATES PATENT OFFICE.

WALTER V. TURNER, OF WILKINSBURG, PENNSYLVANIA, ASSIGNOR TO THE WESTING-HOUSE AIR BRAKE COMPANY, OF WILMERDING, PENNSYLVANIA, A CORPORATION OF PENNSYLVANIA.

NUT-LOCK AND SWAB-PROTECTOR.

1,280,335.

Specification of Letters Patent.

Patented Oct. 1, 1918.

Application filed June 29, 1917. Serial No. 177,763.

To all whom it may concern:

Be it known that I, WALTER V. TURNER, a citizen of the United States, residing at Wilkinsburg, in the county of Allegheny and 5 State of Pennsylvania, have invented new and useful Improvements in Nut-Locks and Swab-Protectors, of which the following is a specification.

This invention relates to combined nut 10 locks and swab protectors, and more particularly to a protector adapted for use on locomotive steam pumps.

It has heretofore been proposed to provide a combined nut lock and swab 15 protector comprising hinged sections adapted to be operated by handles for inclosing the swab and the gland nuts of the pump piston rod, but in some types of steam pumps, there are certain projecting parts which interfere with the installation of a swab 20 protector of the necessary length to properly inclose the gland nuts as desired.

The principal object of my invention is to overcome the above difficulty by providing 25 a longitudinally collapsible swab protector which can be collapsed while inserting the same in position and then allowed to expand so as to properly cover the parts to be protected.

30 In the accompanying drawing; Figure 1 is an elevational view of a portion of a steam pump, showing the improved swab protector as it is being inserted in position; Fig. 2 a side elevation, partly in section, of 35 the swab protector, showing the parts in the normal expanded position; and Fig. 3 a plan view thereof.

As shown in the drawing, the construction 40 may comprise semi-cylindrical sections 1 and 2 hinged together by means of a hinge pin 3 and having operating handles 4 and 5 secured respectively to the sections 1 and 2, a coil spring 6 being mounted on the pin 3 and being adapted to yieldingly hold the 45 hinged sections in the closed position.

Slidably mounted for vertical movement within the sections 1 and 2 are semi-cylindrical sections 7 and 8 having headed pins 9 secured thereto and adapted to work in vertical slots 10 cut in the sections 1 and 2. 50

The sections 1, 2, 7, and 8 are provided with vertical ribs 11 adapted to engage within the usual slots of the gland nuts 12 for locking the nuts against rotation.

In use, the sections 7 and 8 normally rest 55 in their collapsed or telescoped positions, being held there by gravity, and when it is desired to apply the swab protector, the handles 4 and 5 are grasped and brought together, so as to open up the hinged sections 60 1 and 2. The device is then placed in position, and due to the sections being collapsed, the protector can be moved into position over obstacles, such as the bosses 13, shown in Fig. 1 of the drawing. 65

After the device is in position surrounding the pump piston rod, the handles being released, a ledge 14 at the upper edge of the sections 7 and 8 rests on top of the projections 15 of the upper nut 12 and the sections 70 1 and 2 drop down by gravity, so as to completely inclose the lower gland nut 12, the positions of the parts being then as shown in Fig. 2 of the drawing.

Having now described my invention, what 75 I claim as new and desire to secure by Letters Patent, is:—

1. A swab protector comprising semi-cylindrical members hinged together, handles for operating the same and additional semi-cylindrical members mounted within and adapted to have a vertical movement relative to the hinged members. 80

2. A combined nut lock and swab protector comprising semi-cylindrical members hinged together, additional semi-cylindrical members telescopically mounted within said hinged members, said members having projections for engaging the gland nuts of the pump. 85

In testimony whereof I have hereunto set my hand.

WALTER V. TURNER.
